UNITED STATES PATENT OFFICE

2,448,770

DRIER HEATING SYSTEM

Richard D. Cheesman, Allentown, Pa., assignor
to Traylor Engineering & Mfg. Co., Allentown,
Pa., a corporation of Delaware

Application June 15, 1943, Serial No. 490,920

4 Claims. (Cl. 263—15)

1

Certain slurries of the character used in the manufacture of cement, especially those with high water content, are difficult to calcine because their physical characteristics change as the moisture is extracted. Some of them become extremely tacky and adhere to the interior surface of the kiln forming what is known to the trade as slurry or mud rings. On this account it has been found desirable to pre-dry the slurry to a moisture content at which this tackiness is avoided in the calcining operation. A satisfactory form of drier for this purpose is disclosed in Patent No. 1,992,520, granted February 26, 1935, to Colton and Lang. The drier of the said patent is adapted to be arranged in receiving relation to the hot waste gases flowing from the kiln so that these gases are used as the sole heating means for the drier.

In such an arrangement a complication arises in that the temperature and heat content of the waste kiln gases vary on account of several factors, for example, the radiation losses from the kiln shell, the chemical composition and reaction of the material being calcined or sintered, the variation of the moisture content of the slurry, and the fineness of the material. All of these factors influence the regulation of the kiln burner and thus cause variations in the heat content and temperature of waste or flue gases from the kiln.

In the above-mentioned patent, control is attempted to be maintained by means of dampers disposed in the conduit leading from the kiln to the drier and in a by-pass conduit. However, these provisions are inadequate to afford the required pre-drying temperature when the total heat effect of the waste kiln gases is inadequate, and it is the object of the present invention to provide means whereby requisite drying heat is assured. To this end I provide means for supplying supplemental heat to the drier, the supplemental supply being preferably automatically regulated and inversely in dependence upon the temperature of the waste gases flowing from the kiln, and at least being controlled by reference to the temperature of these gases. I also provide dampers in the supply and by-pass conduits and these may be automatically adjustable independently with the auxiliary heat supply. The improvements are shown in illustrative embodiments

ment in the accompanying drawings to which reference will now be made. In these drawings,

Figure 1 is an elevation, partly in section, of an installation in accordance with the invention:

Figure 2 is a section substantially on line 2—2 of Figure 1;

Figure 3 is an axial section of a drier which appears in Figure 1, and

Figure 4 is an end elevation of the drier of Figure 3 as seen from the left of that figure.

Referring to the drawings, reference numeral 11 designates a conventional rotary kiln, and 12 a regulable burner. The latter may be of any suitable design and, for example, may be like that shown in my prior Patents No. 1,949,560 or No. 1,989,665. The feed end of kiln 11 is disposed in a side opening of a chamber 13 provided with an opposite opening in which is set an elbow 14 forming part of a waste flue which includes an upright by-pass conduit section 15. Above chamber 13 is a drier generally designated by reference numeral 16.

The drier 16 comprises a rotary drum 17 having at its ends tires 18 and 19 supported on rollers 20 and 21, the drum being driven from a motor 22 and gearing terminating at a ring gear 23 secured to the drum. The drum is surrounded by a housing 24 comprising a peripheral shell 25 and annular end walls 26 and 27 provided with channeled inner edges in which are engaged annular flanges 28 and 29 on the drum, this interleaving arrangement providing relatively gas-tight joints. Inwardly of the flanges 28 and 29 the drum is provided with circumferential series of openings 30 and 31 and, just inwardly of these latter, with inwardly projecting annular flanges 32 and 33. Just outwardly of the openings 30 and 31 the drum is provided with inwardly projecting annular flanges 34 and 35 which form a relatively gas-tight joint with circular end walls or plates 36 and 37 fixedly supported on brackets 38 and 39.

A shaft 40 journaled in bearings 41 and 42 extends through openings in walls 36 and 37 and the bottom of the drum, and is adapted to be driven from a motor 43. Shaft 40 is parallel to the drum axis and beneath the latter. Within flanges 32 and 33 shaft 40 carries two series of paddles or arms 44 and 45. A feed spout 46

extends through an opening in wall 37 and is downwardly and inwardly inclined with its delivery end adjacent the top of the paddles 45 on the down-traveling side of the latter. Material delivered through the spout to the interior of the drum is agitated by the paddles 44 and 45 and is moved by the paddles, which are suitably formed for the purpose, over the bottom of the drum in opposite directions to discharge over the bottom portions of rings 32 and 33 to drop through openings 30 and 31 and through openings 47 and 48 of the housing shell 25 to drag conveyors 49 and 50 which deliver to a screw conveyor 51, Figure 1. The latter delivers to a spout 52 which is passed through the top of chamber 13 and into the feed end of the kiln.

Leading upwardly from elbow 14 to an opening 54 in the bottom of the housing shell 25, is a conduit 53 having a flared upper portion 53'. Fixed to the interior of the housing between opening 54 and the openings 30 of the drum is an annular radially arranged baffle 55 which substantially closes the space between the housing and the drum. Hot gases supplied through conduit 53 will thus flow completely around the drum periphery so that the latter will be heated throughout. Restrained by baffle 55 against escape through drum openings 30, the gases will then flow to the drum interior through openings 31, escaping through openings 30 to an exhaust opening 56 in the top of shell 25 between wall 26 and baffle 55 whence the gases pass through an elbow 57, Figure 1, to a conduit or flue 58 into which the by-pass conduit 15 is connected. Radial wings 17' and 17'' on the drum keep the conduits through which the gases pass and the material is discharged clear at the ends, preventing the spray from building up and filling the lower parts.

Reference numeral 57', Figure 1, designates a dust conveyor in receiving relation to chamber 13 and elbow 14 through conduits 58' and 59, which may be dampered.

Portion 53' of conduit 53 has an opening 60 against the outer margins of which is set the open end of the combustion chamber 61 of a burner or booster furnace 62. A fuel nozzle 63 for gas or oil, for example, is disposed at the other end of chamber 61 and is equipped with a control valve 64 including a rotary spindle 65 by rotation of which the fuel supply may be regulated progressively between zero and maximum. A valved line 66 is connected into the valve 64 from the fuel supply.

Located in conduit portion 53' is a thermostat 67 projecting into the conduit to one side of the stream of hot gases. The reactions of the thermostat are communicated to a controller 68 through a line 69, the controller having a rock shaft 70 actuated in response to the thermostat. Shaft 70 is parallel to the spindle 65 and carries a two-armed lever of which one arm 71 is connected by a link 72 with an arm 73 fixed on the spindle. In the relation of the parts shown in Figure 1 the controller is assumed to have been operated to maximum, shaft 70 turning clockwise, so that the fuel supply to the burner 62 is at maximum.

Arm 71 is also connected through a link 73' with an arm 74 on the shaft of a damper 75 in by-pass conduit 15, and with valve 64 fully open, the damper is in the fully closed position shown.

The other arm 76 of the controller lever is connected by a link 77 with an arm 78 on the shaft of a damper 79 in conduit 53, the damper being

wide open in conformity with the wide open position of the valve 64 and the closed position of damper 75.

Should the temperature of the flue gases rise, controller shaft 70, as affected by the reaction of the thermostat, will turn in a counter-clockwise direction so that valve 64 and damper 79 will be accordingly moved toward closed position whereas damper 75 will be accordingly moved in the opening sense. Thus, with the hookup as illustrated, the auxiliary fuel supply valve and the two dampers are interdependently and automatically operated to control the heat supply to the drier inversely in dependence upon the temperature of the flue gases. Links 73' and 77 can be removed so that the dampers can be independently manually operated, or automatic operation can be applied to only one of the dampers by removing the operating link for the other. If it should be desired to operate valve 64 manually, for example, upon failure of the thermostat, the link 72 is removed and valve 64 is then manually adjusted by reference to a thermometer 80 set in conduit portion 53' adjacent the thermostat.

By reason of the regulable auxiliary heat supply, uniform drying conditions are maintained at the drier and the resulting slurry fed to the kiln is of uniform temperature and moisture content, insuring the calcining operation in the kiln under the most favorable conditions. The usual rings of accretions at the feed end of the kiln are entirely eliminated.

While I have disclosed the invention in preferred embodiment it will be understood that it is not necessarily limited to the described form and relation of the parts and that variations are possible and are contemplated under the claims which follow.

I claim:

1. In combination, a kiln, means for supplying heat to the kiln, a drier for slurry to be fed to the kiln, a conduit for leading the hot gases from the kiln to the drier, a by-pass conduit, dampers in said conduits respectively, an auxiliary heater with variable output arranged to deliver to said first mentioned conduit, whereby to supplement the heat of said gases, and means for interdependently controlling said heater and dampers.

2. In combination a kiln, means for supplying heat to the kiln, a drier for slurry to be fed to the kiln, a conduit for leading the hot gases from the kiln to the drier, a by-pass conduit, dampers in said conduits respectively, an auxiliary heater with variable output arranged to deliver to said first mentioned conduit, whereby to supplement the heat of said gases, and means responsive to the temperature of said gases for interdependently controlling said heater and dampers in a manner to augment the heat supply to the drier when said temperature falls.

3. In combination, a kiln, means for supplying heat to the kiln, a drier for slurry to be fed to the kiln, a conduit for leading the hot gases from the kiln to the drier, a by-pass conduit, dampers in said conduits respectively, an auxiliary burner arranged to deliver to said first mentioned conduit, whereby to supplement the heat of said gases, a fuel supply valve for said burner, and means for interdependently operating said valve and dampers.

4. In combination, a kiln, means for supplying heat to the kiln, a drier for slurry to be fed to the kiln, a conduit for leading the hot gases from the kiln to the drier, a by-pass conduit, dampers

in said conduits respectively, an auxiliary burner arranged to deliver to said first mentioned conduit, whereby to supplement the heat of said gases, a fuel supply valve for said burner, a controller operated in response to the temperature in the first-named conduit, and operating connections from said controller to said valve and dampers.
